US0D1039842S

(12) **United States Design Patent** (10) **Patent No.:** **US D1,039,842 S**
(45) **Date of Patent:** **** Aug. 27, 2024**

(54) **HEAD FOR ELECTRIC TOOTHBRUSH**

(71) Applicant: **Braun GmbH**, Kronberg (DE)

(72) Inventors: **Niclas Altmann**, Niddatal (DE); **Jens Alinski**, Kelkheim (DE)

(73) Assignee: **Braun GmbH**, Kronberg (DE)

(**) Term: **15 Years**

(21) Appl. No.: **29/836,827**

(22) Filed: **Apr. 29, 2022**

Related U.S. Application Data

(62) Division of application No. 29/699,695, filed on Jul. 29, 2019, now Pat. No. Des. 953,744.

(57) **CLAIM**

The ornamental design for a head for electric toothbrush, as shown and described.

DESCRIPTION

FIG. 1 is a perspective view of a head for electric toothbrush; FIG. 2 is a front elevation view thereof;

FIG. 3 is a right-side elevation view thereof;

FIG. 4 is a rear elevation view thereof;

FIG. 5 is a left-side elevation view thereof;

FIG. 6 is a top plan view thereof;

FIG. 7 is a bottom view thereof; and,

FIG. 8 is an enlarged partial perspective view thereof.

Broken lines are used in the drawings to designate environmental structures or parts of the head for electric toothbrush that form no part of the claim.

1 Claim, 3 Drawing Sheets
